(57) CLAIM

The ornamental design for a spray bottle for Bar-B-Q, as shown and described.

DESCRIPTION

FIG. 1 is a perspective view of the bottle;
FIG. 2 is a top view of the bottle, the bottom has no special characteristics which cannot be deduced from the other views and is therefore not included;
FIG. 3 is a side elevation of the left side of the bottle as per FIG. 5;
FIG. 4 is a side elevation of the right side of the bottle as per FIG. 5; and,
FIG. 5 is a front elevation of the bottle with the back side elevation being a mirror image.
